UNITED STATES PATENT OFFICE

OSWALD C. BREWSTER AND WILLIAM M. PERRY, OF CASPER, WYOMING, ASSIGNEES
TO STANDARD OIL COMPANY, OF WHITING, INDIANA, A CORPORATION OF INDIANA

ART OF TREATING HYDROCARBON OILS

Application filed March 22, 1931. Serial No. 263,767.

The present invention relates to improvements in the art of treating hydrocarbon oils, and will be fully understood from the following description, illustrated by the accompanying drawing, in which apparatus for carrying the invention into effect is diagrammatically illustrated.

The apparatus disclosed in this application is covered in our co-pending application, Serial No. 263,766, for improvements in apparatus for treating hydrocarbon oils.

Referring more particularly to the drawing, A indicates a still in which the oxidizing operation is carried on; B indicates a pipe still; and C, a flash drum.

The still A is divided by partition 1 into compartment 2 and compartment 3, and the two chambers communicate with each other through the overflow pipe 4 with which the partition 1 is provided. By means of the overflow pipe 4, which projects upwardly into chamber 3, a body of liquid may be held in the bottom of compartment 3. Compartment 2 is provided with a draw-off pipe 5, a perforated pipe 6 through which air or other oxygen-containing gas may be introduced into the still, and a pipe coil 7 located exteriorly to the still and communicating therewith through pipes 8 and 9. Pipes 8 and 9 are each equipped with valves by which communication with the still may be cut off. A pump 10 may be employed to circulate oil from the compartment 2 through pipe 8 and the coil 7 back into the still through pipe 9.

Compartment 3 is equipped with baffles 11 which are preferably inclined downwardly so that the fresh oil which is introduced near the top of the chamber through pipe 12 may be caused to follow a zig-zag path through the length of the compartment. Vapors are drawn off through vapor line 13 and condensed in the condenser 14 from which the condensate flows into the receiver 15. The receiver is provided with a gas release line 16 and a liquid draw-off 17.

Both compartments of the still A are equipped with man-holes 18 which are closed by plates 19. By means of the two man-

holes, the still may be cleaned when desired. Still A is preferably lagged.

The pipe still B communicates with the lower portion of compartment 3 through pipe line 20. Pipe 20 is provided with a valve 21 and a pump 22 which may be employed to force material withdrawn from compartment 3 through the pipe still and into the flash drum C. A steam line 23 joins pipe 20. It is preferred, however, to introduce steam at an intermediate point in pipe still B.

The flash drum C communicates with the pipe still B through pipe line 24. The drum is equipped with a spreader-cone 25 and a vapor line 26. The vapors may be drawn off through the vapor line 26 and condenser 27, and the condensate recovered in the receiver drum 28, which is equipped with gas release line 29 and liquid draw-off line 30. The flash drum C is also equipped with a residuum draw-off line 31 through which heavy material at the bottom of the flash drum may be returned to compartment 2. The draw-off line is provided with a valve 32.

In the operation of the process, feed stock enters compartments 3 of the still A through line 12 and after filling the bottom portion of the compartment, overflows into compartment 2, the valve 21 in line 20 preferably being closed. When the compartment 2 has been filled to the point at which pump 10 may take suction through line 8, the oil is circulated through the heating coil 7 until the oil has been brought to a suitable temperature, say 600° to 650° F. or higher, at which oxidation will begin on the supplying of air to the still. When the oil in the still has reached a suitable temperature, air is supplied through the line 6 in such volume as to maintain the desired temperature in the still. Circulation of the oil through the heating coil 7 is then discontinued. It is preferred to supply fresh oil continuously through pipe 12 so that the descending stream of oil, which follows a zig-zag course along the baffles 11, makes contact with the vapors that are generated in compartment 2 and pass into compartment 3 through overflow line 4.

The fresh oil is thus stripped of its lightest ends which, together with the lighter frac-

tions of the vapors from compartment 2, pass up through vapor line 13, are condensed in condenser 14 and recovered in receiver 15. The heavier fractions of the vapors from compartment 2 are condensed and returned with the stripped feed stock to the pool in the bottom of compartment 3. From the body of oil thus formed, a stream of oil is pumped through pipe still B in which the temperature of the oil is raised to any desired high temperature, as, for example, about 800° F., to produce a gas oil distillate. Steam is introduced into the oil from line 23 just before it enters the pipe still. The highly heated oil and steam, after leaving the pipe still B, pass through line 24 and are discharged preferably upon a spreader-cone 25. Vapors generated in the flash drum pass through vapor line 26, are condensed in coils 27 and recovered in receiver 28. The residuum is drawn off through line 31 and returned to compartment 2 where it is subjected to the oxidation operation. Material in the bottom of compartment 2 may be withdrawn continuously or intermittently through the valve controlled residuum line 5.

If desired, the valve 21 in line 20 may be kept closed and the operation carried on without using the pipe still and flash drum. In this method of operation, the excess of the stripped feed stock and condensed heavier fractions of the vapors, which form the pool in the bottom of compartment 3, may pass into the oxidizing chamber 2 through the overflow pipe 4.

The return line 31 from the flash drum is preferably lagged so that the material returned therefrom to compartment 2 may retain as much of its heat as possible. If the oil is raised to high temperatures in the pipe still and the hot unvaporized portions returned directly in a lagged conduit to the oxidation chamber, the added heat assists materially in keeping the oil in compartment 2 at the temperature at which the oxidizing operation may be carried on.

The process is particularly useful in running to coke certain refractory stocks, such as the black oils of Wyoming. It is well known, that in the distillation of such stocks, the gas oil cut obtained is dirty and unsatisfactory as charging stock for a pressure still, since the oxidation carries by entrainment large amounts of coky material into the vapor. In the operation of the process herein disclosed, a charging stock for pressure stills is obtained that is quite satisfactory. The coky material is trapped by the fresh feed in compartment 3 along with the heavier gas oil fractions which are condensed. Also, on continuous distillation with steam in pipe still B the gas oil is redistilled and recovered as clean distillate from C, while the coky material remains in the residue and is recycled to the oxidizing chamber 2. The operation

is preferably continued until compartment 2 is full of coke.

It is not intended that the details of the process, as above set forth, shall be regarded as limitations upon the scope of the invention except in so far as included in the accompanying claims.

We claim:

1. The method of treating hydrocarbon oils which comprises maintaining a body of oil, heating said body of oil until the oil body is brought to a temperature of active oxidation in the presence of a free oxygen containing gas, supplying within the body of oil controlled quantities of free oxygen containing gas whereby said body of oil is maintained at the desired temperature, contacting the vapors evolved therefrom with an incoming stream of fresh oil, thereby condensing the heavier portions of said vapors, collecting said condensed vapors and fresh oil to form a separate body of oil, passing oil from said separate body in a confined stream through a heating zone, discharging said stream of oil into an enlarged chamber and separating the vapors therefrom, removing said vapors, and returning the unvaporized fractions of the oil to the first mentioned body of oil. 85

2. The method of treating hydrocarbon oils which comprises, maintaining a body of oil, heating said body of oil until the oil body is brought to a temperature of active oxidation in the presence of a free oxygen containing gas, supplying within the body of oil controlled quantities of free oxygen containing gas whereby said body of oil is maintained at the desired temperature, contacting the vapors evolved therefrom with an incoming stream of fresh oil, thereby condensing the heavier portions of said vapors, collecting said condensed vapors and fresh oil to form a separate body of oil, withdrawing oil from said separate body, introducing steam into said withdrawn oil, and passing said withdrawn oil and steam in a confined stream through a heating zone, discharging said stream of oil into an enlarged chamber and separating the vapors therefrom, removing said vapors, and returning the unvaporized fractions of the oil to the first mentioned body of oil. 100

3. The method of treating hydrocarbon oils which comprises, maintaining a body of oil, heating said body of oil until the oil body is brought to a temperature of active oxidation in the presence of a free oxygen containing gas, supplying within the body of oil controlled quantities of free oxygen containing gas whereby said body of oil is maintained at the desired temperature, contacting the vapors evolved therefrom with an incoming stream of fresh oil, thereby condensing the heavier portions of said vapors, collecting said condensed vapors and fresh oil 115

- to form a separate body of oil, passing oil from said separate body in a confined stream through a heating zone, discharging said stream of oil into an enlarged chamber and separating the vapors therefrom, removing said vapors, returning the unvaporized fractions of the oil to the first mentioned body of oil. 5
4. The method of treating hydrocarbon oils which comprises maintaining a body of oil, heating said body of oil until the oil body is brought to a temperature of active oxidation in the presence of a free oxygen containing gas, supplying within the body of oil controlled quantities of free oxygen containing gas whereby said oil is maintained at the desired temperature, contacting the vapors evolved therefrom with an incoming stream of fresh oil, thereby condensing the heavy portions of said vapors, collecting said condensed vapors and fresh oil to form a separate body of oil, passing oil from said separate body in a confined stream through a heating zone, discharging said fresh oil into an enlarged chamber, removing the vapors therefrom, and returning the unvaporized portions hot to said body of oil. 10
5. The method of producing a clean distillate charging stock from a heavy asphaltic crude which comprises, maintaining a body of oil, heating said body of oil until the oil body is brought to a temperature of active oxidation in the presence of a free oxygen containing gas, supplying within the body of oil controlled quantities of a free oxygen containing gas whereby the oil body is maintained at the desired temperature, contacting the vapors evolved therefrom with fresh oil, thereby condensing the heavier portions thereof, collecting said condensed portions and fresh oil in a separate pool, withdrawing a stream of oil from said pool, introducing steam into said stream of oil, passing said oil and steam through a heating zone, discharging said stream into an enlarged chamber, separating the vapors therefrom, and returning the unvaporized portions to said body of oil. 15
6. The method of treating hydrocarbon oils which comprises, maintaining a body of oil, heating said body of oil and then supplying thereto a free oxygen containing gas to maintain said oil at conversion temperatures, removing the vapors evolved therefrom, contacting said vapors with a stream of incoming fresh stock, thereby stripping said fresh stock of light vapors and condensing the heavy portions of said evolved vapors, removing the said stripped vapors and the lighter fractions of said evolved vapors, collecting the condensed heavier fractions of said evolved vapors and said stripped fresh stock in a separate body of oil, passing oil from said separate body in a confined stream through a heating zone, discharging said
- stream of oil into an enlarged unheated chamber and separating the vapors therefrom, removing said vapors, and returning the unvaporized fractions of the oil to the first mentioned body of oil. 20
7. The method of treating hydrocarbon oils which comprises, maintaining a body of oil, heating said body of oil and then supplying thereto a free oxygen-containing gas to maintain said oil at conversion temperatures, removing the vapors evolved therefrom, contacting said vapors with a stream of incoming fresh stock, thereby stripping said fresh stock of light vapors and condensing the heavy portions of said evolved vapors, removing the said stripped vapors and the lighter fractions of said evolved vapors, collecting the condensed heavier fractions of said evolved vapors and said stripped fresh stock in a separate body of oil, withdrawing oil from said separate body, introducing steam into said withdrawn oil and passing said withdrawn oil and steam in a confined stream through a heating zone, discharging said stream of oil into an enlarged unheated chamber and separating the vapors therefrom, removing said vapors, and returning the unvaporized fractions of the oil to the first mentioned body of oil. 25
8. The method of treating hydrocarbon oils which comprises, maintaining a body of oil, heating said body of oil until the oil body is brought to a temperature of active oxidation in the presence of an oxidizing gas, supplying within the body of oil controlled quantities of oxidizing gas whereby said oil is maintained at the desired temperatures, removing the vapors evolved therefrom and contacting them with a stream of fresh oil whereby said oil is preheated, withdrawing said preheated fresh oil and passing it through a heated zone and then into an enlarged chamber, removing vapors therefrom, and returning the unvaporized portions hot to said body of oil. 30
